DESIGN FOR A CREAM PITCHER OR SIMILAR ARTICLE

Nettie E. Graven, Wooster, Ohio

Application November 12, 1947, Serial No. 142,470

Term of patent 14 years

(Cl. D44—21)

To all whom it may concern:

Be it known that I, Nettie E. Graven, a citizen of the United States, residing at Wooster, in the county of Wayne and State of Ohio, have invented a new, original, and ornamental Design for a Cream Pitcher or Similar Article, of which the following is a specification, reference being had to the accompanying drawing, forming part thereof.

Fig. 2 is a front elevational view thereof; and
Fig. 3 is a side elevational view thereof.

The dominant features of my design reside in the part shown in full lines in the drawing.

I claim:

The ornamental design for a cream pitcher or similar article, substantially as shown and described.

NETTIE E. GRAVEN.
